UNITED STATES PATENT OFFICE.

BRODERICK HASKELL, OF SAGINAW, MICHIGAN.

BRAKE-BEAM.

SPECIFICATION forming part of Letters Patent No. 707,105, dated August 19, 1902.

Application filed June 18, 1902. Serial No. 112,143. (No model.)

To all whom it may concern:

Be it known that I, BRODERICK HASKELL, of Saginaw, in the county of Saginaw and State of Michigan, have invented a certain 5 new and useful Improvement in Brake-Beams, of which improvement the following is a specification.

The object of my invention is to provide a 10 brake-beam which shall embody the features of strength, lightness, and inexpensiveness of construction and in which the connection of the compression and tension members may be effected in a simple and convenient manner and without the possibility of accidental 15 detachment.

The improvement claimed is hereinafter fully set forth.

In the accompanying drawings, Figure 1 is 20 a plan view of a brake-beam, illustrating an embodiment of my invention, with one of the brake-heads detached; Fig. 2, a side view of the same; Figs. 3 and 4, transverse sections at the lines *x x* and *y y*, respectively, of Fig. 1; Fig. 5, a view in elevation of one of the 25 brake-heads when attached to the beam; Fig. 6, a side view of a connecting-rivet, and Fig. 7 an end view of the same.

In the practice of my invention the compression member or body 1 of the brake-beam 30 is preferably, as shown, formed of stout sheet-steel or other metal pressed or bent into **U** or channel section and is, as usual, slightly inclined or curved from its middle portion toward each of its ends. The tension or truss member 2 is in this instance shown as formed 35 of a metal bar of rectangular section, for which, if desired, a rod or rods may be substituted, and is bent or inclined in opposite directions from its middle to its end portions.

40 A strut or king-post 3 fits at one end over the middle portion of the compression member, and the tension member may either pass through an eye at the opposite end of the strut or fit in a recess therein, as preferred.

45 The ends of the tension member 2 are turned over into the form of hooks 2^a, which fit between the side plates of the compression member 1 at each of its ends and are secured thereto and to the brake-heads 4, which fit 50 over the ends of the compression member by transverse connecting members, which are preferably, as shown, rivets 5, made of ellip-

tical transverse section or elongated on an axial plane designed to be in line with the compression member, so as to afford greater 55 strength and increased bearing-surface, and which pass through the eyes of the hooks 2^a and through slots 6 in the side plates of the compression member and corresponding slots in the brake-heads and are turned over on 60 the latter. A simple and rigid connection of the parts is thus effected and liability to their accidental displacement in service is fully obviated.

It will be clear to the skilled mechanic that 65 a key would be the mechanical equivalent of the rivet above described and may be substituted therefor, if desired, without departing from the spirit of my invention.

The strut 3 is secured to the compression 70 member by a rivet 7, passing through perforations in the sides of the compression member and through a filling or distance piece 8, which is fitted between the side plates thereof at its middle portion to maintain the side 75 plates at the normal distance apart.

In operation the draft of the tension member is exerted upon the connecting members—*i. e.*, the rivets or keys—and is thence transferred to the brake-heads and from the brake- 80 heads to the compression member.

A substantial advantage is attained by the elimination of the nuts which are ordinarily employed in the connection of the parts, as well as by the simplicity and compactness of 85 the end connections of the beam.

I claim as my invention and desire to secure by Letters Patent—

1. In a brake-beam, the combination of a compression member of **U** or channel section, 90 a tension member having hooked ends fitting between the side plates of the compression member, transverse connections, passing through the eyes of the hooked ends of the tension member and through the side plates 95 of the compression member, and a strut interposed between the middle portions of the compression and tension members.

2. In a brake-beam, the combination of a compression member of **U** or channel section, 100 a tension member having hooked ends fitting between the side plates of the compression member, transverse connections which are elongated in cross-section in the line of the

compression member, and which pass through correspondingly-formed slots in the side plates of said member and through the eyes of the hooked ends of the tension member, and a 5 strut interposed between the middle portions of the compression and tension members.

3. In a brake-beam, the combination of a compression member of **U** or channel section, a tension member having hooked ends fitting 10 between the side plates of the compression member, brake-heads fitting over the ends of the compression member, transverse connections passing through the brake-heads, the side plates of the compression member, and 15 the eyes of the hooked ends of the tension member, and a strut interposed between the middle portions of the compression and tension members.

4. In a brake-beam, the combination of a compression member of **U** or channel section, 20 a tension member having hooked ends fitting between the side plates of the compression member, brake-heads fitting over the ends of the compression and tension members, rivets passing through the brake-heads, the side 25 plates of the compression member, and the eyes of the hooked ends of the tension member, and having heads abutting on the brake-heads, and a strut interposed between the middle portions of the compression and ten- 30 sion members.

BRODERICK HASKELL.
